UNITED STATES PATENT OFFICE.

CHARLES E. WEBSTER, OF WINTHROP, MINNESOTA.

RAILWAY-FREIGHT-CAR DOOR.

Application filed July 20, 1922. Serial No. 576,317.

To all whom it may concern:

Be it known that I, CHARLES E. WEBSTER, a citizen of the United States, residing at Winthrop, in the county of Sibley 5 and State of Minnesota, have invented certain new and useful Improvements in Railway-Freight-Car Doors; and I do declare the following to be a full, clear, and exact description of the invention, such as will enable others skilled in the art to which it appertains to make and use the same.

This invention relates to an improved door which is especially designed for use on railway freight cars, and the same may be 15 conveniently referred to as a grain door, although it is equally well intended for use when sand or other granular material is being shipped.

The principal object of the invention is 20 to generally improve upon closures of this class by providing one of extreme simplicity and durability which is composed of comparatively few and inexpensive parts to render the door inexpensive to both the manufacturer and the user.

It is another object and aim to produce a door of this class which will absolutely prevent leakage of the grain while in transit, the door being such in construction that it 30 is held in operative position by the pressure of the grain against it, but is permitted to collapse when the lower boards are removed.

More specifically speaking, it is a further 35 object of the invention to devise a novel grain door composed of duplicate sections bearing at their outer ends against the car body and arranged to diverge toward their inner ends, the last named ends being engageable with a novel sustaining member 40 which is interposed between them, this means being such in construction that it facilitates assembling of the closure, securely retains the parts in operative relation, and 45 permits automatic collapsing when the lowermost boards are removed.

A still further object of the invention is 50 to produce a unique door or closure which does not require any fastenings, hangers, or special mounting means.

Other objects and advantages of the invention will be apparent during the course 55 of the following description.

In the accompanying drawings forming 60 a part of this specification and in which

like numerals are employed to designate like parts throughout the same:

Figure 1 is an elevational view of a door 60 constructed in accordance with this invention showing the same in use.

Figure 2 is a horizontal section, the door 65 being shown in plan.

Figure 3 is a similar view showing a modified construction of car body and manner in which the improved door co-acts therewith.

Figure 4 is an enlarged elevational view 70 of the novel sustaining member showing more clearly the manner of connecting it with the bottom of the car body and the manner in which the lower boards are released.

Figure 5 is a detail view of the lower end 75 of the sustaining bar, with parts in section showing more clearly the improved device for maintaining the lowermost boards in operative position.

Figure 6 is a detail perspective view of this sustaining bar or member.

Figure 7 is a vertical section taken on 80 the line 6-6 of Fig. 1.

Figure 8 is a detail perspective view of a portion of one of the stops of the car body against which the door sections bear.

Figure 9 is a perspective view of the floor 85 plate, with which the lower end of the sustaining bar is connected.

In the drawings, the letters B designate the side walls of a car body, the letter O represents the door opening, P designates 90 the vertical door posts, and S represents the stops which are secured to these posts in the manner shown.

Briefly described, the invention resides 95 in the employment of a novel closure for the opening O in the side of the car body. The closure preferably embodies duplicate sections formed of inner and outer rows or layers of boards arranged with their longitudinal edges in abutting relation.

These boards are detachably connected with one another and at their outer ends, they 100 rest against the door posts P and stops S. At their opposite ends however, they are spaced from one another and diverge toward each other. In this space, novel sustaining means in the form of a bar is positioned, this means being connected with the bottom of the car in a manner to permit 105 it to be swung inwardly to facilitate as- 110

sembling of the boards and outwardly to permit the boards to bind tightly against it when the grain exerts pressure against the inner boards. The sustaining member 5 embodies a retractable part which cooperates with the lowermost boards and permits these to be removed to permit the grain to 10 out into the carrier or other suitable means in which it is desired to deposit it.

10 Specifically described, the improved door or closure comprises the duplicate sections represented by the reference characters 1. As before briefly indicated, each section is composed of inner and outer layers or rows 15 of comparatively short horizontally disposed boards 2 which have their longitudinal edges arranged in abutting relation to permit them to be disposed in vertical alinement. It may be conveniently stated 20 here that the lowermost board of the inner row is not as wide as the corresponding board of the outer row (see Fig. 7). It is therefore obvious that the boards of the two rows become disposed in staggered relation. Hence, the boards of the 25 inner row serve to cover the cracks between the boards of the remaining row. Consequently, the closure is thus rendered leak-proof. As seen clearly in the drawings and 30 as hereinbefore pointed out, the boards 2 rest at their outer ends against the door posts and stop strips which are secured to these. At their opposite diverging ends however they engage with a novel sustaining 35 member which is very clearly illustrated in Fig. 6. Although this member could be of some other construction, it is preferably in the form of an I-beam 3 having relatively narrow and wide inner and outer 40 flanges 4 and 5 respectively. It is between these flanges that the inner diverging ends of the boards 2 are confined. Of course, in order to permit easy assembling 45 of the boards, it is necessary that the beam be connected with the car body in a manner to permit it to be moved inward to the approximate dotted line position shown in Fig. 4. I therefore have devised novel 50 means for connecting the beam at its lower end with the floor F of the car body. The means preferred comprises a substantially rectangular plate 6 which is screwed or otherwise securely fastened to the floor over a recess 7 formed in the latter. Al- 55 though it is not essential, it is desirable to have the plate flush with the upper face of the floor. As seen clearly in Fig. 9, this plate is formed with a substantially cross-shaped slot 8 and inasmuch as a portion of 60 the web 9 of the aforesaid beam projects beyond the adjacent ends of the flanges 4 and 5, and as this extended part is enlarged at 10 and carries a cross pin 10^a, it will be seen that by passing said part through the 65 slot with the pin engaging the underface of

the plate beneath the longitudinal portion of said slot, a pivotal and detachable connection for the beam will be had. With such a connection, the beam is capable of being slid a slight distance inwardly or 70 outwardly as required in some instances. Also, the beam can be entirely removed from the car to prevent the door opening from being obstructed by its presence. It is obvious that the aforesaid recess 7 serves 75 to accommodate the enlarged lower end 10 of the beam which extends into it, and permits swinging or sliding of the beam. At this point, it may be logically mentioned 80 that any suitable means (not shown) may be employed for connecting the upper end of the beam with the car. In most instances however, this means can be dispensed with entirely as it is not altogether necessary.

It has been before intimated that this 85 novel sustaining beam or bar is equipped with unique retractable retaining means for cooperation with the lowermost boards for holding these in operative position, this retaining means being such that as soon as it 90 is released, it permits the lowermost boards to be displaced from the door opening and permits collapsing of the entire structure for discharging the grain from the car. This retractable retaining device could be of 95 some other construction, but it is preferably in the form of a "break-joint" device which is maintained in an operative condition by unique release means. By directing attention to Figure 6, wherein the device under 100 consideration can be more clearly seen, the numeral 11 designates a part which is pivotally connected with the enlargement 12 at the lower end of the wide flange 5. The part 11 is provided with longitudinal flanges 13 which are decreased in size toward the free 105 end of this part 11. By so designing the flanges, they constitute cams which act in a manner to be hereinafter described. Continuing with this break-joint locking device, 110 it will be seen that it also embodies a substantially channel-shaped member 14 which has its flanges extended beyond one end and pivotally connected at 15 to the intermediate 115 portions of the aforesaid flanges 13. The free feather-like end of the part 11 is intended for disposition between the side flanges of the channel member 14 when this locking device is in operative state, and a slidable release device 16 is intended for co-action with the thinned end of this part 11. It is to be noted that this release device 16 embodies a slotted portion 17 which is slidably and pivotally connected with the pin 18 carried by 120 said member 14. As shown in Figures 4 and 5, the release member 16 overlies the free end of the part 11 and serves to prevent relative pivotal movement of the parts 11 and 14. To act in conjunction with this release 125 element 16, the member 14 is equipped on its 130

free end with a reduced portion 19 adapted for reception in the notch 20 formed in the enlarged end 10 of the bar. If desired, in the portion 19 may be formed the small notch 21 for co-action with the key 22 formed in the aforesaid notch 20. To further act in connection with the release element 16, I prefer to equip the flanges of the member 14 with oppositely disposed elongated slots 23 and to pass a locking pin 24 through these slots so as to permit it to extend crosswise of the release element 16 to prevent it from being swung outwardly to the dotted line position indicated in Figure 4. In practice if it is not desired to use a pin for this purpose, a wire having a seal (not shown) connecting the ends together may be employed. As a matter of fact, this is preferred in many instances. By carefully examining the detail 16 it will be seen that when this is slid downwardly to position the pivot pin 18 in the upper end of the slotted portion 17, it will be impossible to swing it to a position to permit breaking of the joint between the parts 11 and 14. However, by sliding the element 16 upwardly to position the pivot pin 18 in the opposite end of the slot, it can be swung to the dotted line position indicated to permit breaking of the joint. I direct attention here to the fact that as the release element 16 is slid upwardly to accomplish this result, the free end thereof rides against the inclined cam-flanges 13 of the part 11 and it is thus moved outwardly sufficiently far to permit it to be engaged by the fingers for swinging upon its pivot to release the part 11. Although it has been inferred that the release 16 will be pulled outwardly by hand, it is understood that any suitable implement or instrument may be used for accomplishing this end.

Directing attention now to other features of this novel sustaining bar, it will be seen that the aforesaid narrow flange 4 is notched at the points 25 and these notches are employed to permit an insert, such as a wedge or the like to be disposed between the ends of the boards and the web of the bar, for the purpose of preventing the latter from tilting too far outwardly to permit assembling of the upper boards of the structure. I also wish to point out that if desired, the web of the bar may be equipped with integral substantially V-shaped ribs 26 which are intended to become embedded in the ends of the boards to assist in holding the latter in place.

To equip a conventional type of freight car with a closure construction in accordance with this invention, it is only necessary to form the aforesaid recess 7 in the floor F a slight distance inward of the adjacent outer edge of the floor, the recess being disposed at the proper point intermediate the ends of the door opening O. The anchoring

plate 6 is then secured to the floor with the cross-shaped slot thereof disposed over the recess. This plate is to be permanently left in position. With the plate in place, the sustaining beam or member 3 is brought into play, the pin 10 being passed through the transverse part of the slot 8 and the beam being moved outwardly to position the pin beneath the longitudinally disposed portion of this slot as evident from Fig. 4. Assuming that the beam has been thus connected with the floor of the car body, the next step is to tilt the same inwardly so that it assumes an inclined position. When in this position, the several boards 2 can have their inner ends placed between the flanges 4 and 5. It is advisable to arrange the beam so that the relatively narrow flange is on the inner side, as the inner ends of the boards will more readily clear it. The boards are placed in from the top of the beam and are dropped down into their proper position as is obvious. I advocate placing the boards only up to a certain height so as to permit the grain to be inserted through the opening between the uppermost boards and the top of the car. Since the grain would have a tendency to tilt the upper end of the sustaining bar outwardly when the grain reaches a certain height in the car, I contemplate, as before indicated, placing an insert, such as a wedge or the like against the web of the bar at the point where the flange 4 is notched as at 25. The ends of the boards then bear against the insert instead of directly against the web of the beam and the grain cannot push the latter outwardly to a degree which would prevent completion of the door by inserting the upper boards. Of course, after the rest of the boards are put in position, the insert can be removed so that the beam will be permitted to move outwardly under the influence of the grain to bind the inner ends of all of the boards against the ribs of the beam. The grain thus functions to maintain the closure in place.

Assuming that it is desired to discharge the grain from the car to a suitable carrier or the like, it is only necessary to remove the locking pin 24 or seal, whichever is employed, so as to permit the release 16 to be moved in a manner to permit breaking of the joint of the locking device. After the pin 24 has been removed, this release 16 is moved upwardly and in so doing, the free edge thereof is engaged with the inclined edges of the flanges 13 of the part 11 and the free end of the release is automatically moved away from the bottom of the member 14. An instrument can then be inserted between the release 16 and part 11 and the former swung outwardly upon its pivot so as to permit relative pivotal movement of the parts 11 and 14. After the release is swung

outwardly and the part 11 freed, the force of the grain against the lowermost boards automatically breaks the joint of this novel locking device and the parts assume the approximate positions shown in dotted lines in Figure 4 and in full lines in Figure 6. After a certain amount of grain has been discharged through the opening provided by the removal of the lowermost board of the closure, the entire closure will collapse to permit the remainder of the grain to be readily discharged.

It is manifest from the foregoing description that I have evolved and produced a novel closure for door openings on freight cars which is especially adaptable for use when grains and other granular materials are being shipped. As before intimated, the closure is economical in cost and in maintenance, it is substantially leak-proof and such in construction that it does not require special fastenings and mounting means. The closure is adjustable for different size openings and is entirely removable from the opening to prevent the same from being obstructed. The construction is also such that the vibrations and jars caused by the movement of the car will serve to pack the material tighter and to bind the boards of the closure against their respective abutments to produce a tight and effective closure.

For the purpose of illustration, I have shown in Fig. 3, a slightly modified construction of car body, wherein the stops S' are secured to the inner faces of the sides of the body so as to permit the ends of the boards to bear against them instead of against the posts as hereinbefore described. In this showing, the posts P' act in the manner that the stops S do as also set forth. It is therefore desirable to form the posts with such an arrangement at their lower ends with notches to facilitate displacement of the lower sets of boards when the grain is being discharged. So far as the construction of the closure is concerned, no change is necessary as this will accommodate either construction of car body and will be effective for use in closing openings of various sizes.

In cases where the floor of the car is very irregular, packing, such as paper 27 (see Fig. 7) may be placed between the closure and the floor to prevent leakage of grain.

A closure embodying the expedients described is advocated, but it is understood that the foregoing description is not controlling in all respects, for minor changes coming within the scope of the annexed claims may be resorted to if desired.

I claim:

1. A collapsible closure including a plurality of disconnected boards arranged in vertical alinement with their longitudinal

edges in abutting relation, the outer ends of these boards bearing against the car body, and a sustaining member cooperable with the opposite ends of the boards, said member having a retractable retainer co-operating with the lowermost boards to permit removal thereof when it is desired to discharge the grain from the car, whereby to permit collapsing of the entire structure.

2. A closure of the class described comprising a vertically disposed inwardly tiltable I-beam, and a plurality of separate disconnected boards arranged in a vertical row with their longitudinal edges arranged in abutting relation, said boards bearing at their outer ends against the car body and having their opposite inner ends confined between the flanges of the beam, said beam having a retractable retaining part at its bottom to permit displacement of the lowermost boards, whereby to cause automatic collapsing of the entire structure.

3. A closure of the class described comprising an I-beam designed to be detachably and pivotally connected at its lower end with the floor of a car body, a pivoted locking plate associated with the lower end of said beam, and a plurality of disconnected boards arranged horizontally and disposed in a vertical row, the outer ends of the boards bearing against the car body and the inner ends being confined between the flanges of the beam, with the lowermost boards disposed in rear of said hinged plate to permit them to be displaced when said plate is moved to releasing position.

4. In a closure of the class described, an I-beam having one flange terminating a considerable distance upward of its lower end with the other flange terminating a short distance inward of said end, anchoring means connected with that part of the web projecting beyond the ends of said flanges, and retaining means hingedly connected with the short flange and occupying a considerable space between this end of the flange and the adjacent end of the web.

5. In a closure of the class described, a sustaining bar embodying a retractable break-joint retaining device comprising a part pivotally connected to the bar and a substantially channel-shaped part pivotally connected to the intermediate portion of the first named part, and a slidably release device pivotally mounted on the second named part and cooperable with the first named part to prevent relative pivotal movement of the two parts.

6. In a closure of the class described, a sustaining device in the form of an I-beam having relatively wide and narrow flanges, the last named flange being provided intermediate its ends with opposed notches to receive a wedge-like insert, and the web of said

beam being provided at vertically spaced points with transverse ribs to be embedded in the inner ends of the boards which are adapted to be disposed between said flanges.

5 7. In a closure of the class described, an anchoring plate formed with a substantially cross-shaped slot, and a sustaining bar for a plurality of boards adapted to have its web portion projected through said slot, and a 10 pin connected with said bar and extending at right angles therefrom, said pin being intended to be passed through the short transverse portion of said slot, and drawn beneath the long portion of the slot to connect the bar with the plate.

8. In combination, a car body having a door opening in one side, and a closure for said opening, said closure being composed of duplicate inwardly converging sections, 20 each of which is composed of a plurality of separate disconnectible boards arranged in a vertical row with their longitudinal edges engaging one another, the outer ends of the boards bearing against the car body, and 25 means interposed between the inner ends of said sections for maintaining them in operative position, said means being pivotally connected at its lower end with the floor of the car body to permit it to be tilted to the

proper angle to facilitate assembling of the 30 boards.

9. Sustaining means of the class described comprising an I-beam having relatively wide and narrow flanges between which the ends of the boards of closure sections are 35 adapted to be confined, one of said flanges terminating short of the lower end of the beam, the latter being provided at its lower end with an enlarged head carrying laterally disposed anchoring studs; and a break-joint retaining device for the lowermost boards of the closure sections, said device comprising a part pivotally connected to the lower extremity of the aforesaid short flange, a substantially channel-shaped part 40 which is pivotally connected to the intermediate portion of the first named pivoted part, and a slidale release device pivotally connected with the second named part and disposed between the side flanges thereof, 45 said slidale release device being adapted to engage the first named pivoted part to prevent relative pivotal movement of both of said parts.

In testimony whereof I have hereunto affixed my signature.

CHARLES E. WEBSTER.
